UNITED STATES PATENT OFFICE

RAYMOND MALCOLM DAVID BUTTON, OF COLEFORD, BATH, ENGLAND

MINE AND LIKE SIGNALING APPARATUS

Application filed September 30, 1931, Serial No. 565,987, and in Great Britain October 9, 1930.

This invention relates to a new or improved mechanical signaling apparatus, particularly for use in mines. Mechanical signaling apparatus for such purposes have certain advantages over electrical signaling apparatus, but also have certain drawbacks which the present invention obviates. In a usual form of mechanical signaling apparatus, the onsetter by operating a handle or lever a certain number of times according to a pre-arranged code of signals, causes a bell to be sounded as many times as the handle is operated near the banksman and the driver of the winding engine and to operate an indicator near the driver to visibly indicate the signal. The motion between the parts of the apparatus is transmitted by a wire or cable and bell crank levers, and since the distance between the onsetter and banksman may be relatively great there is a certain amount of lost motion, consequently the correct signal is not always given to the driver, which drawback is also overcome by the present invention.

A signaling apparatus according to the present invention comprises a fixed dial having a series of radial divisions, one for each signal, a handle provided with a pointer moving round said dial, a revoluble plate carried behind said dial and adapted to be moved in one direction by the handle which is returned to its normal position by a spring and overruns the plate, a plurality of wings, teeth or projections on the plate, a bell crank lever, the one end of which is successively engaged by said wings, teeth or projections as the plate is revolved, in such manner that the lever is moved or oscillated a number of times corresponding to the number of divisions over which the handle has been moved and a transmitting wire or cable connected to the other end of the bell crank lever for operating a signaling bell or bells and/or indicator. A spring controlled compensating device is preferably inserted within the length of the transmitting wire or cable.

In practice, the onsetter is provided with one such device and the banksman with two, one for signaling to the driver and one to the onsetter, the transmitting wire or cable being

so connected that the banksman's bell and the driver's bell ring together.

This invention will be now more particularly described making reference to the accompanying drawing in which:—

Fig. 1 is a view in side elevation of a signaling apparatus embodying the present invention.

Fig. 2 is a view in plan thereof, and

Fig. 3 is a view in end elevation thereof.

Throughout the views similar parts are marked with like letters of reference.

In the constructional form, shown by way of example, a frame *a*, which is rigidly fixed in any convenient manner to a framing or timbers at the desired position, has attached thereto a dial plate *b* which may be conveniently of the shape shown. This plate *b* is radially divided into equal divisions *b*¹, say 11 for example as shown, one division for each signal. Each division *b*¹ may be numbered from 0 to 10 and also be provided with corresponding divisions *b*² which are printed with various signals, for instance under No. 1 "Raise", under No. 2 "Lower", under No. 3 "Men on", and so on.

On the frame *a*, at the centre of the dial *b*, is fixed a stud axle *c* on which is mounted free to revolve thereon a plate *d* made in one with or attached to a ratchet wheel *e*. The plate *d* is provided with equally spaced wings, projections or ratchet teeth *d*¹ as shown by way of example. The number of teeth in the ratchet wheel *e* are preferably equal to the number of ratchet teeth *d*¹ or their equivalent, and the pitch of the teeth *d*¹ are equal to the radial divisions on the dial *b*. A lever or handle *f* is mounted, so as to be capable of angular movement about the axis of the dial *b*, between the dial *b* and the plate *d* and is furnished with a hand or pointer *f*¹ moving over the divisions on the dial *b*.

The lever or handle *f* is controlled by means of an adjustable spring *f*² so that after being operated it always returns to a normal or zero position of rest against a stop *a*² carried on an auxiliary frame *a*³ on the frame *a*. The downward movement of the lever *f* is limited by a stop *a*⁴ also carried by an arm on the frame *a*. The rocking lever or handle *f* is

provided with a spring controlled pawl f^3 arranged to engage the ratchet wheel e anchored to the plate d when moved in one direction but overruns the teeth of said ratchet wheel e when the handle or lever is released and is returned to its zero position by means of its spring f^2 . A bell crank lever g is pivoted at g^1 to the frame a in such position that one of its ends—preferably provided with a roller g^2 —is in the path of the teeth d^1 on the plate d so that as the latter revolves, each of said teeth causes an angular movement of the lever g . The other end of said lever g is provided with a number of holes g^3 any one of which may be connected to the transmitting wire or cable α . A stop or buffer a^5 is provided on the frame a to limit the downward movement of the roller end of the lever g , which stop or buffer may be faced with a resilient material. As the most common signal in use is one stroke of the bell, a movable stop h is preferably provided to limit the movement of the rocking lever or handle f necessary to make such a signal. The movable stop h may take the form of a pin carried by a chain or flexible connection and engaging a hole in the frame a^3 so as to project in the path of the lever f . In operation, on moving the handle or lever f until its head or pointer f^1 agrees with the number or signal to be transmitted, say No. 7 on the dial b , the bell crank lever g will have been moved seven times, thus causing the bell or bells to be sounded seven times and the indicator—which forms no part of this invention—near the winding engine to visibly indicate the signal No. 7. The indicator which is preferably used comprises a single stroke bell which is sounded each time the transmitting wire or cable is operated in combination with a pointer moving over a dial lettered and numbered to correspond with the dial b . The hammer of the bell is provided with a spring controlled trip lever which engages a pawl to operate a ratchet wheel. The pointer of the dial is carried by the ratchet wheel so that the signal is given visibly and audibly. The pointer remains to indicate the last signal given until a fresh signal is transmitted, whereupon the pointer flies back to zero before the bell is sounded. The compensating device to take up the slack of the transmitting wire or cable is such that the movement at the operative end of the wire or cable α is greater than that required at its other end to sound the bell, for instance if the movement required to sound the bell is a stroke of six inches, then the movement of the operative lever is a stroke of nine inches, the difference being taken up by an adjustable spring. One such arrangement of compensating device, see more particularly the right hand side of Fig. 1, comprises a yoked frame i , the upper end i^1 of which is attached to the wire or cable α passing to the bell and/or in-

dicator mechanism. A transverse plate i^2 free to slide on or between the side members of the frame i carries a centrally arranged screw threaded rod i^3 passing freely through a bearing in a fixed plate i^4 connecting the lower ends of the members of the frame i together. The lower end of the rod i^3 is connected directly to the wire or cable α from the transmitting mechanism, or indirectly by means of a bell crank lever α^2 . Compression springs i^5 encircle the side members of the frame and the rod i^3 and act between the sliding plate i^2 and the fixed plate i^4 , and the strength of the springs i^5 and the movement of the rod i^3 with respect to the frame i is adjusted by means of a nut i^6 threaded on the rod i^3 and contacting with the upper surface of the sliding plate i^2 of the frame.

I declare that what I claim and desire to secure by Letters Patent is:—

A mine and like signaling apparatus comprising a fixed dial, a series of radial divisions, one for each signal, on said dial, a revoluble plate carried behind said dial, a handle rotatable on the axis of the dial and plate, a pointer carried by the handle and movable over the division on said dial, a one way clutch for clutching the handle to the plate, a spring arranged to return the handle to its normal position of rest after operation, movable stops to limit the movement of the handle, a plurality of teeth or projections on the plate corresponding to the pitch of the divisions on the dial, a bell crank lever, the one end of which is successively engaged by said teeth or projections as the plate is rotated, so that the lever is moved or oscillated a number of times corresponding to the number of divisions over which the pointer on the handle has been moved, a transmitting wire or cable connected to the other end of the bell crank lever for operating a signaling bell or indicating means and a spring controlled compensating device interposed within the length of the transmitting wire or cable, as set forth.
